UNITED STATES PATENT OFFICE.

JACOB BURKAM, OF BROOKLYN, NEW YORK.

BED-PAN.

1,093,530.

Specification of Letters Patent. Patented Apr. 14, 1914.

Application filed January 28, 1911. Serial No. 605,310.

To all whom it may concern:

Be it known that I, JACOB BURKAM, a citizen of the United States, residing at Brooklyn, in the county of Kings and State 5 of New York, have invented new and useful Improvements in Bed-Pans, of which the following is a specification.

This invention relates to bed pans, and the object of the invention is to provide an 10 article of this character which is of a simple and durable construction and which is so formed as to effectively sustain itself upon the mattress of a bed and to accommodate itself to the anatomy of the patient so that 15 the said pan may be used with comfort.

Another object of the invention is the provision of a bed pan having a substantially flattened base or bottom, curved sides and a 20 top or seat curved at its rear portion and sloping toward the front of the pan, the sides of the pan adjacent the rear portion thereof being inclined toward the edge of the curved portion of the top and the pan is provided with a door or closure for the 25 space between the rear wall and the curved edge of the seat so that splattering of the bed clothing is prevented and also whereby the contents of the pan may be emptied without danger of spilling. The normally 30 closed portion also provides a means whereby the parts of the patient using the pan become accessible for treatment by the nurse.

With the above objects in view, the invention resides in the novel construction and 35 formation of bed pans hereinafter set forth and particularly pointed out in the claim, hereunto appended.

In the accompanying drawings, Figure 1 is a perspective view of a bed pan constructed in accordance with the present invention. Fig. 2 is a central, longitudinal view of the same.

The numeral 1 designates the bed pan, which is preferably constructed of some 45 suitable non-corrosive metal such as galvanized iron, block tin, aluminum or the like. This pan has its bottom portion 2 substantially flattened at the center thereof, while its forward end converges gracefully 50 from the said central portion and its rear is formed in an abrupt curve which terminates a considerable distance above the front edge and this curved portion forms what may be termed the rear wall of the pan.

55 The sides 3, which are connected in any desired manner with the edges of the bot-

tom, are bulged outwardly at their central portions and from thence converge in opposite directions toward both the front and rear of the bottom. The sides 3 at their rear 60 portions have their upper edges inclined downwardly a suitable distance from their points of connection with the rear and upturned portion of the device formed by the bottom 2, as designated by the numerals 4, 65 and are from thence curved upwardly as at 5. The sides are vertically straight and are from their upwardly curved portions continued downwardly in a substantially straight line, terminating in almost a point 70 at the front edge of the bottom 2.

The top plate 6, may, if desired be formed from the same sheet of material as the bottom 2 and the said top is shaped to correspond to the shape of the sides to which the 75 edges of the top are secured. The top 6 is provided with the usual opening and the said top terminates at the points of juncture of the inclined edges 4 and the upturned portions 5 of the sides 3. By this arrangement it will be noted that an open space is 80 left between the seat or top and the rear wall of the pan, and this space is normally closed through the medium of a door 7, which is hingedly connected as at 8 with the 85 edge of the downwardly curved end of the top or seat 6.

All of the edges of the pan are smooth or rounded and from the above description taken in connection with the accompanying 90 drawing, it will be noted that the pan is so adapted as to be readily slid beneath the patient; that the door 7 arranged below the plane of the seat provides means whereby the parts of the patient projecting through 95 the opening of the pan may be treated while the pan is in use; that the upwardly curved end of the pan directs the contents thereof away from the body of the pan, when the latter is emptied; and that the cover 7 not 100 only serves as a baffle to assist in the direction of the matter from the pan, but also prevents the escape of odor from the pan when in use.

Having thus fully described the invention, 105 what I claim as new, is:-

A bed pan comprising a bottom having its rearward portion gradually extending upwardly and forming the rear wall of the pan, sides secured to the bottom and being 110 higher than the rear wall at a point spaced inwardly from and above the rear wall, and

from thence extending downwardly to a point adjacent to and below the terminal end of the rear wall, and from thence abruptly inclined upwardly to the terminal end of the rear wall, a seat secured to the sides and terminating at the juncture where the sides are abruptly inclined upwardly, a cover hingedly connected to the terminal end of the seat and adapted to close the space be-

tween the seat and the rear wall, the said cover being limited in its path of movement by the seat.

In testimony whereof I affix my signature in presence of two witnesses.

JACOB BURKAM.
